(57) **CLAIM**

The ornamental design for an animal bedding, as shown and described.

DESCRIPTION

FIG. 1 is a front perspective view shown of a first embodiment of an animal bedding showing our new design; FIG. 2 is a front elevation view thereof; FIG. 3 is a rear elevation view thereof; FIG. 4 is a bottom plan view thereof; FIG. 5 is a top plan view thereof; FIG. 6 is a left side elevation view thereof; FIG. 7 is a right side elevation view thereof; FIG. 8 is another front perspective view shown in an alternate configuration of an animal bedding; FIG. 9 is a front perspective view shown of a second embodiment of an animal bedding showing our new design; and, FIG. 10 is a front elevation view thereof.

Broken lines, including the diamond shaped broken line illustrative of stitching shown in FIGS. 1-2 and 8-10, the broken lines illustrative of stitching shown around the perimeter of the animal bedding in FIGS. 1-3 and 8-10, and the broken lines of a guinea pig as an environmental structure and form no part of the claimed design.
